UNITED STATES PATENT OFFICE.

EDWARD D. CONKLIN, OF NEWARK, NEW JERSEY, ASSIGNOR TO THE WHITEHEAD & HOAG COMPANY, OF NEWARK, NEW JERSEY, A CORPORATION OF NEW JERSEY.

PIN-RECEIVING DEVICE.

1,153,175.

Specification of Letters Patent.

Patented Sept. 7, 1915.

Application filed January 21, 1913. Serial No. 743,268.

To all whom it may concern:

Be it known that I, EDWARD D. CONKLIN, of Newark, in the county of Essex, in the State of New Jersey, have invented new and useful Improvements in Pin-Receiving Devices, of which the following, taken in connection with the accompanying drawings, is a full, clear, and exact description.

This invention relates to a pin-receiving device, and pertains more particularly to the formation of a handy and useful toilet article of unitary manufacture, having an annular retaining rim for confining a mirror and provided with perforations for receiving pins.

A further object is to provide a pad for holding the mirror in contact with the annular retaining rim and at the same time for retaining pins extending through the perforations in said rim.

Other objects and uses will appear from the following description.

In the drawings: Figure 1 is a perspective view of the combined mirror and pin cushion. Fig. 2 is a cross section on line 2-2, Fig. 1. Fig. 3 is a perspective view of the annular retaining rim.

The annular retaining rim —1— is provided with a laterally extending flange —2—. A mirror —3— rests against this flange and is confined thereby. At the rear of the mirror is preferably placed a sheet of stiffening material —4—, as cardboard. The sheet —4— is supported and held in place by a penetrable pad —5—, preferably cotton batting.

The annular retaining rim —1— is provided with a plurality of openings —6— extending through the wall thereof at the rear of the plane of the mirror —3—, and if a stiffening sheet —4— is used, preferably as shown at the rear thereof, for receiving pins

—7— which are retained therein by engagement with the pad —5—. The pad —5— is preferably supported by a second sheet of cardboard or other suitable material —8— and a cap or cover —9— is adapted to fit over the rear edge of the retaining rim —1— and is preferably frictionally held in engagement with said rim for holding the mirror, strengthening sheets and pad in operable relation.

It is readily apparent that the rim —1— may be provided with openings of different sizes and that the number of these openings may vary without departing from the spirit of the invention, as set forth in the appended claim. It is further evident that the retaining rim —1— is not necessarily a circular rim, but may be of any form such as oval, rectangular or square.

What I claim is:

In a pin-receiving device, an annular collet having one edge inturned to form a circumferential flange, a plurality of openings at the rear of the flange adapted for receiving pins, a panel fitted within the collet and having its edge resting against said flange, a protective sheet at the rear of said panel, a pad of puncturable material fitted within the collet and supported on one side by the protective sheet, a second supporting sheet within the collet at the opposite side of the pad, and a cap having a circumferential flange adapted to frictionally engage the other edge of said collet and hold the supporting sheets, the puncturable pad and the panel in operable position.

In witness whereof I have hereunto set my hand this 7th day of January, 1913.

EDWARD D. CONKLIN.

Witnesses:

WM. A. JONES,
M. H. SADLER.
